TOOTHBRUSH

Charles H. Graves, Jr., San Diego, Calif., assignor
to The Jetbrush Corporation, San Diego, Calif.,
a corporation of California

Application July 5, 1949, Serial No. 3,711

Term of patent 14 years

(Cl. D9—2)

To all whom it may concern:

Be it known that I, Charles H. Graves, Jr., a citizen of the United States, residing at San Diego, in the county of San Diego and State of California, have invented a new, original, and ornamental Design for a Toothbrush, of which the following is a specification, reference being had to the accompanying drawing, forming part thereof, in which—

Fig. 1 is a perspective view of a toothbrush, showing my new design;

Fig. 2 is a side elevational view thereof;

Fig. 3 is a bottom plan view thereof; and

Fig. 4 is an end elevational view thereof looking to the bristle end of the toothbrush.

I claim:

The ornamental design for a toothbrush, as shown.
